INVENTOR

BY *Victor J. Evans*

WITNESS:

R. E. Wise

ATTORNEY

UNITED STATES PATENT OFFICE.

JOHN S. HEMMING, OF SALT LAKE CITY, UTAH, ASSIGNOR TO FIDELITY RADIO CORPORATION, OF SALT LAKE CITY, UTAH.

BASE FOR LOUD-SPEAKER UNITS.

Application filed January 15, 1927. Serial No. 161,376.

The invention relates to improvements in sound reproducing units especially adapted for use in loud speakers for radio receiving apparatus, although the invention is capable 5 of application to other types of sound reproducers.

An object of the present invention is the provision of novel means for mounting and securing the diaphragm of the reproducer in 10 place, so that the diaphragm will be housed in such manner as to render the same practically immune from tampering, yet will be readily accessible by the use of a proper tool.

With the above and other objects in view, 15 the invention further includes the following novel features and details of construction, to be hereinafter more fully described, illustrated in the accompanying drawings and pointed out in the appended claims.

20 In the drawings:—

Figure 1 is a sectional view showing a reproducer unit with the invention applied.

Figure 2 is a section taken substantially on the line 2—2 of Figure 1.

25 Referring to the drawings in detail wherein like characters of reference denote corresponding parts, the invention is shown in connection with a power reproducing unit, although it is not the purpose of the present 30 application to restrict the invention to a unit of this type. The invention is equally well adapted for other types of units and the illustration is merely for the purpose of explaining the construction and advantages of the 35 invention.

The invention as shown comprises a substantially cup-shaped member 10 which includes an annular flange 11, the latter extending around the edge and forming a mem-

40 ber or receptacle of the character mentioned. The cup-shaped member is provided with a sound escape opening 12 which is surrounded by a threaded nipple 13 and the latter is adapted to have secured thereto a horn or like 45 sound distributing member, a portion of which is illustrated at 14.

Located within the cup-shaped member is a diaphragm 15 of suitable character and

the latter is spaced from the inner wall of the cup-shaped member by means of a rubber or 50 other gasket 16. This gasket extends around the edge of the diaphragm 15 upon the inner face thereof, while a similar gasket 17 is likewise arranged upon the opposite face of the diaphragm. Bearing upon the gasket 17 55 is a flat ring 18 so that the gaskets 16 and 17 act to hold the diaphragm 15 spaced with respect to the ring 18 and the inner wall of the cup-shaped member 10.

The flange 11 is provided with an annular 60 groove 19 and this groove has removably positioned therein a split spring wire retaining ring 20 which bears against the flat ring 18. The diaphragm 15 is thus securely held in place and may only be removed with the 65 aid of a suitable tool to affect the removal of the ring 20.

The member 10 is designed to be placed in the top of a suitable receptacle 21 and is provided with an annular shoulder 22 which 70 bears against the upper edge of the receptacle 21. Contained within the receptacle is a pair of electromagnets 23 which are operatively associated with the diaphragms as shown at 24, so that when these magnets are energized 75 they will actuate the diaphragm in a manner well understood. Suitable means may be provided for holding the cup-shaped member 10 within the receptacle, the means shown consisting of screws 25 and 26, the former 80 having one end engaged within one of the threaded openings 27 provided in the ring 18 and its opposite end mounted as indicated at 28, while the screw 26 is threadedly en- 85 gaged in the other opening 27 and has threaded engagement with one of the brackets 29 of the electromagnets 23.

The invention is susceptible of various changes in its form, proportions and minor details of construction and the right is herein 90 reserved to make such changes as properly fall within the scope of the appended claim.

Having described the invention what is claimed is:—

In a reproducer unit, a receptacle, a cover 95 for the top of the receptacle, said cover hav-

ing a sound escape opening therein, a flange carried by the cover and extending into the top of the receptacle and having an annular groove upon its inner face, a diaphragm with-
5 in the flange and spaced from the cover, a gasket bearing upon the diaphragm, a cross sectionally flat ring within the flange and bearing upon the gasket, a split ring within the groove of the flange to hold the parts as-

sembled, actuating means for the diaphragm, 10 means within the receptacle to mount said actuating means, and means connecting the flat ring with the means to mount the dia- phragm actuating means to hold the parts 15 assembled.

In testimony whereof I affix my signature.

JOHN S. HEMMING.
